UNITED STATES PATENT OFFICE.

HELEN SANTORINAOS CARSON, OF STAMFORD, CONNECTICUT.

HEATER FOR WASHING-MACHINES.

1,341,109.

Specification of Letters Patent.

Patented May 25, 1920.

Application filed May 14, 1919. Serial No. 297,131.

To all whom it may concern:

Be it known that I, HELEN S. CARSON, a citizen of the United States, and a resident of Stamford, in the county of Fairfield 5 and State of Connecticut, have invented a new and Improved Heater for Washing-Machines, of which the following is a full, clear, and exact description.

This invention relates to a heater which 10 is more particularly applicable to washing machines, and aims to provide a device of this nature wherein the soapy water usually wasted may be heated again and reused.

It is a well-known fact that a great 15 amount of unnecessary expense is incurred in connection with a washing machine of the centrifugal-drive type in that the same must be drained prior to the drying of the objects washed, resulting in the wastage of a 20 great amount of fluid thoroughly impregnated with soap to form a highly cleansing fluid.

Aside from this, a great amount of time is wasted in the replenishing of the waste 25 water with fresh water which has been properly heated and in thoroughly comingling this water with particles of soap so as to form a good mass of suds with which to clean the clothes.

30 Aside from the foregoing defects, a great strain is exerted upon the operator, in that he, or she, is compelled to carry each successive filling of water to the machine, which is a very wearing task, especially if the operator is not robust.

Having the above in mind, I have constructed a washing-machine heater which may be associated with the washing machine in such a manner that one filling of the 40 heater with water and soap will be sufficient for an entire washing.

Another object of this invention is the provision of means associated with the heater for maintaining the fluid at a proper 45 temperature.

A further object of the invention is the association of a heater with a washing machine in such a manner that the fluid used in connection with the washing machine 50 may be drained from the heater into the washing machine, or vice versa, which results in a maximum of economy.

A still further object of the invention is the provision of means connected with the 55 heater which will cut off the heating element when the heater has had all the fluid

drained out of it, so that no danger of an overheating of the heater exists; but when the fluid is drained from the washing machine back into the heater, the heating 60 means is again turned on, it being understood, however, that this heating-medium controlling device may be entirely eliminated, if so desired.

Having these objects in view, I have constructed a device in accordance with the same, one practical embodiment of which is represented in the attached sheet of drawings, in which—

Figure 1 is a side view of a washing machine with a heater associated therewith;

Fig. 2 is a plan view of the heater; and

Fig. 3 is a plan view of the heating element for the heater.

In all of these views like reference numerals designate similar parts, and the reference numeral 1 indicates the exterior casing of any convenient type of washing machine, which may be supported by legs 2, although I preferably mount the same upon 75 a permanent base so that the device becomes a fixture of the house in which it is placed, the washing machine being driven by any suitable motor 3, the usual basket-raising foot lever 4 being also provided. 80

Located adjacent to the washing machine there is a fluid heating tank 5 which is slidably mounted along supporting columns 6, the same being suspended from a shaft 7 which may be rotated by means of a hand 90 crank 7' provided with restraining means such as a pawl 7''. The shaft 7 is formed with a drum 8 around which passes a chain 9 having its lowermost end secured to a crossbar 10 fastened to the tank 5. 95

The columns 6 are supported by a base 11, which may be provided with feet 12; and also supported by this base is a battery of burners 13 provided with individual controlling valves 14 and a single controlling 100 valve 15. The single controlling valve 15 may, or may not, be eliminated from the construction, but the same is acted upon by means of a rod 16.

The fluid heating tank 5 is formed adjacent its lower end with an opening, from which projects a pipe 17, and provided with a valve 18, the washing machine being likewise formed with an outlet pipe 19 and a control valve 20 therefor. Extending between the valves 18 and 20 is, preferably, a piece of flexible tubing, such as 21, through

which fluid may drain from the washing machine into the tank 5, or vice versa.

In operation it will be seen that, assuming that it is desired to dry the clothes in the washing machine and at the same time to heat the fluid which has been employed therein, all that it will be necessary for the operator of the device to do will be for him to release the ratchet 7" and permit a rotation of the shaft 7, whereby the tank 5 will move from the position indicated in Fig. 1 in dotted lines to the position indicated in full lines and the fluid will drain from the washing machine into the fluid heating tank 5. Simultaneously with this operation, the rod 16 will have actuated the valve 15 and the battery of burners 13 will begin to operate so as to properly heat the fluid within the tank 5. In this connection it is to be understood that the valves 20 and 18 are normally open and are provided merely in case a break should occur in the flexible tubing 21, which would render repair necessary, and by providing these valves it will readily be seen that I can easily prevent the flow of fluid from either the fluid heating tank 5 or the casing 1.

It is also to be appreciated that I might desire to continue the operation of the burners individually or as a whole when the tank 5 is in raised position. In this instance, the automatic valve 15 might be entirely eliminated, or thrown out of operation by any suitable provision, and the burners controlled by means of the individual valves 14; and the burners could now be employed as heaters for irons or for any other suitable purpose.

It is further to be understood that although I have shown my fluid heating tank in connection with a centrifugal drying washer, I could readily employ the same in conjunction with any type of washing machine now in existence. Also, although I have disclosed a hand crank and rotatable drum for elevating the tank 5, I wish it un-

derstood that I might employ any suitable elevating means for the tank 5, my idea distinctly embodying the provision of a fluid heating tank in conjunction with a washing machine suitable for domestic purposes in which a minimum of structure is provided to properly drain water from the washing machine, heating the same, and redraining this water back into the washing machine. 50 55

Having thus described my invention, I desire to claim:

1. A device of the class described, including a washing machine, a heater positioned adjacent the same, a tank associated with said heater, and means for raising and lowering said tank. 60

2. A device of the class described, including a washing machine, a heater positioned adjacent the same, a tank associated with said heater, means for raising and lowering said tank, and means affording communication between the tank and washing machine. 65

3. A device of the class described, including a washing machine, a heater, a tank associated with such heater, an outlet located adjacent the bottom of both the washing machine and tank, a flexible piece of tubing extending between such outlets, and means associated with the tank for moving the 70 same in a vertical plane. 75

4. A device of the class described, including a washing machine, a heater positioned adjacent the same, a tank, capable of being moved in a vertical plane, associated with said heater, means for affording communication between the washing machine and the tank, and means associated with the tank and coöperating with the heater for regulating the flame produced by the heater. 80 85

5. A device of the class described, including a washing machine, a heater, a tank associated with such heater, and means for permitting the flow of fluid from such washing machine into the tank, and vice versa. 90

HELEN SANTORINAOS CARSON.
